FOOTWEAR

Nicholas Menutole, Chelsea, Mass.

Application December 11, 1936, Serial No. 115,395

1 Claim. (Cl. 36—1.5)

My present invention relates to footwear, and more particularly to a combination of footwear and leggin which provides a tight joint between the leggin and the rim of a specially designed 5 rubber footwear.

The principal object of my invention therefore, is an improved footwear;

Another object is an improved footwear in combination with an improved leggin, and

10 Other objects and novel features comprising the construction and operation of my device will be apparent as the description of the same progresses.

Referring to the drawing illustrating the preferred embodiment of my invention,

Fig. 1 is a fragmentary side elevation of the combined leggin and rubber footwear;

Fig. 2 is an enlarged cross-section taken on the line 2—2 of Fig. 1;

20 Fig. 3 is a disengaged view of the parts shown in Fig. 2, and

Fig. 4 is a fragmentary side elevation of the leggin removed from the rubber footwear.

Referring more in detail to the drawing, 10 indicates a rubber foot covering, commonly referred to as, a rubber. The rubber 10 in all respects, excepting the rim which surrounds the opening in the top, may be similar in every respect to the conventional rubber. Instead of 25 having a plain rim, as in the conventional rubber, I have formed flange 11 which provides an endless track 12 substantially round in cross-section and having an entrance opening 13 reduced in width. Preferably the material comprising this flange 11 is composed of a stiff but 30 resilient material, as rubber. A leggin member 14 is provided, preferably of thin waterproof material, the bottom flanged edge of which is composed of resilient material, such as rubber. 35 Preferably the flange 15 should be made of softer rubber than the flange material in the rubber flange 11. The leggin may be as long as desired and as tight or loose fitting as desired, but the 40 lower edge comprising the flange 15 should be slightly shorter in circumference than the rubber flange 11. The flange 15 is provided with a recess 16 adapted to receive the lip 17 of the flange 11, and a lip 18 which is adapted to be 45 inserted in the recess 12 of the flange 11.

The leggin 14 is pulled on over the rubber 10 and the flange 15 is engaged in the flange 11, as shown in Fig. 2. The fact that the flange 15 is slightly smaller in circumference than the flange 11 on the rubber 10 makes the joint formed between the two flanges very tight, and when properly assembled this joint will not leak even when the foot of the wearer is submerged in water above the joint. The leggin 14 may be of very light material above the flange 15 such that a 5 pair of such leggins may be folded up and carried in the pocket of the wearer.

The joint between the flanges 11 and 15 provides a water shed in stormy weather so that 10 rain, snow or other dampness does not wet the 15 limbs below the bottom of a rain coat, and the water which normally runs off of the rain coat in a heavy storm is prevented from reaching the wearer.

Having thus described my invention what I 20 claim as new is.

An improved leggin and foot covering comprising in combination, a rubber foot covering comprising the conventional one piece rubber, the rim surrounding the opening in said rubber comprising an overhanging flange, the bottom edge of said flange being spaced from the side of said rubber, an internal annular channel located between said flange and rubber, the upper portion of said channel being normally wider than the 25 entrance adjacent said bottom edge of said overhanging flange, said bottom edge and overhanging flange being resilient for the purpose of bending outwardly to increase the width of said entrance to said channel, an internal annular 30 flange located on the lower portion of said leggin and being composed of resilient material, the upstanding inner portion of said leggin flange having the same normal cross-sectional area as the 35 annular normal internal channel between said 40 overhanging flange and said rubber, an internal annular channel located between the side of said leggin and said upstanding portion and having the same normal cross-sectional area as the 45 depending portion of the overhanging flange of said rubber, the said flanges being adapted to be interlocked together for the purpose of forming a tight joint therebetween.

NICHOLAS MENUTOLE.
